UNITED STATES PATENT OFFICE.

HUGH H. WHITEHEAD, OF PALMETTO, FLORIDA, ASSIGNOR OF ONE-HALF TO DANIEL M. COURTNEY, OF PALMETTO, FLORIDA.

TOOL.

1,366,987.

Specification of Letters Patent.

Patented Feb. 1, 1921.

Application filed August 12, 1920. Serial No. 402,937.

To all whom it may concern:

Be it known that I, HUGH H. WHITEHEAD, a citizen of the United States, residing at Palmetto, in the county of Manatee and 5 State of Florida, have invented a new and useful Tool, of which the following is a specification.

This invention relates to tools, and more particularly to a tool especially designed for 10 repairing internal combustion engines.

The primary object of the invention is to provide a device of this character which may be applied to a valve, while the same is positioned in its cylinder, for imparting rotary movement to the valve to accomplish the grinding thereof.

A further object of the invention is to provide a tool of this character which may be adjusted for use with valves of various 20 designs and one which may be readily and easily operated.

A still further object of the invention is the provision of a novel form of operating levers, whereby the force of the levers of 25 the operating rod is evenly distributed throughout the body thereof, to eliminate binding of the working parts of the tool.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, may be made within the scope of what is claimed, without departing from the spirit of the invention.

Referring to the drawing:-

Figure 1 is a side elevational view of the 40 tool.

Fig. 2 is a bottom plan view of the head of the bit.

Fig. 3 is a sectional view taken on line 3-3 of Fig. 2.

Fig. 4 is a longitudinal sectional view 45 through one of the housings, and

Fig. 5 is a sectional view taken on line 5-5 of Fig. 4.

Referring to the drawing in detail, the 50 reference character 5 designates the body portion of the tool, which is in the form of a relatively long rod having the opposed spiral grooves 6 and 7 formed therein, the upper extremity of the body portion 5 being supplied with the head 8 which has a swivel connection with the body 5 to permit

movement of the body 5 with relation to the head 8.

On the opposite extremity of the body 5, is a socket member 9 which is of any conventional form, and supports the bit 10, to be hereinafter more fully described.

Operating on the body 5, are the tubular housings 11 and 12, each of which is provided with opposed pintles 13 extending laterally from opposite sides thereof, the pintles being disposed in suitable openings provided in the operating levers, whereby the levers may pivot with relation to the housings 11 and 12 during the operation 70 thereof, and as shown, the upper housing 12 has pivotal connection with the lever 14 between the walls of the yoke 16 forming a part of the lever 14.

The outer extremity of the lever 14 is 75 curved as at 17 and has pivotal connection with the link 18, as at 19, the lower extremity of said link 18 extending inwardly as at 20 so that movement of the operating handle 21, which is carried on one end of 80 the lever 14, will produce a relative movement of the housings 11 and 12, in opposite directions.

In each of the housings 11 and 12 are the opposed springs indicated at 22, each of 85 which springs is curved and engages an arm indicated at 26, there being two of such arms in each housing, the arms being however pivotally supported therein, the upper ends thereof engaging the balls 24 90 which are supported by the camming ring 23 to move the upper ends of the arms 26 to cause the lower ends of the arms to move into predetermined notches 26', formed exteriorly of the sleeve 27. A spirally arranged web indicated at 28' is formed integral within each of the sleeves 27, which web is designed to move in the spiral grooves 6 and 7. From the foregoing it is obvious that when the ring 23 is moved to 95 bring one of the arms 26 into engagement with the notches 26', the housing is moved continuously in one direction, and when the opposite arm is moved to engage the notches, the housing is caused to move in the opposite direction, and when both arms engage the notches, the housing moves alternately from right to left.

The bit employed in connection with the device, is of a particular construction and 110 includes a circular head 27 which is provided with a central opening indicated at

28, which opening provides a clearance for one end of the shank 29, which is provided with an opening adapted to accommodate the transversely extending pin 30, whereby 5 the head and shank are secured together, and since the central opening 28 is of a diameter larger than the diameter of the shank 29, it will be seen that free pivotal movement between the head and shank is 10 permitted.

Pins 30 and 31 are carried by the head 27, and each of these pins is mounted eccentrically of the relatively small heads 32, which heads 32 are disposed in openings formed in 15 the first mentioned head, there being provided threaded members 33 operating in suitable openings formed in the head 27, the members 33 adapted to contact with the relatively small heads 32, to secure the same 20 against rotation within their openings. From the foregoing it is obvious that these heads 32 may be adjusted, whereby the pins carried thereon may be regulated to cause the same to register with the openings usually provided in valve heads.

It will thus be seen that in the operation of the device, movement of the operating handle 21 causes the housings 11 and 12 to move longitudinally of the body 5, in oppo-

site directions, causing the rotation of the 30 bit in opposite directions at predetermined intervals, to the end that the valve, which has connection with the head 27, through the pins 30 and 31, is oscillated in its seat to accomplish the grinding of the valve and 35 insuring a true seating thereof.

Having thus described the invention, what is claimed as new is:—

In a tool, a body portion having opposed spiral grooves formed therein, housings operating on the body portion and having a sleeve movable within each housing, each sleeve having notches formed therein, arms supported within the housings, spring members contacting with the arms and adapted 40 to normally force the arms into the notches, means for moving the arms into and out of operation, and means for moving the housings longitudinally of the body portion to rotate the body portion in opposite direc- 45 tions.

In testimony that I claim the foregoing as my own, I have hereto affixed my signature in the presence of two witnesses.

HUGH H. WHITEHEAD.
